ROLLER SKATE

Ernest Kahlert, Santa Ana, Calif.

Application May 28, 1951, Serial No. 228,681

3 Claims. (Cl. 280—11.22)

1

This invention relates to roller skates, and one object is the provision of a rubber cushioned or spring action roller skate having a continuous series of rollers or wheels each individually and separately cushioned to provide smooth shockless skating and further provided with adjustable means additionally accommodating the skate for figure skating, the skate in use simulating the behavior and functioning of an ice skate.

The skate of this invention is adaptable for use by the young and old alike, and for small children with weak ankles it could be provided with wide rollers or even with double rollers. The instant skate provides far greater comfort to the feet and body of the skater than is usual in roller skates, with consequent greater endurance and pleasure to the wearer.

The above broad as well as additional and more specific objects will be clarified in the following description, wherein characters of reference refer to like-numbered parts in the accompanying drawing. It is to be understood that the drawing is intended solely for the purpose of illustration, and that it is neither desired nor intended to limit the invention necessarily to any or all of the exact details of construction shown or described except insofar as they may be deemed essential to the invention.

Referring briefly to the drawing, Fig. 1 is a side elevational view of a roller skate constructed as an embodiment of this invention, showing also in broken lines the outline of a shoe to which the skate may be attached.

Fig. 2 is a longitudinal vertical sectional view of the skate shown in Fig. 1.

Fig. 3 is a bottom plan view of the skate.

Fig. 4 is a sectional view taken on the line 4—4 of Fig. 2.

Fig. 5 is a view similar to Fig. 4 but showing, instead, a modified cushioning means.

Fig. 6 is a fragmentary longitudinal vertical sectional view of the skate, showing the front end thereof modified by the addition of an adjustable tip or bumper whereby the skate is adapted for use in figure skating.

Fig. 7 is a perspective view of the said adjustable tip or bumper per se.

Referring in detail to the drawing, the numeral 10 indicates the roller skate of this invention, which may, if desired, be provided permanently attached to a shoe 11 as is the usual custom, although it might of course also be provided separately from the shoe and equipped with clamps, not shown, for attaching it to the shoes of the user.

2

The skate 10 comprises the plate 12 on which the shoe 11 rests, and from which spaced vertical side walls 13 extend downward, the walls 13 being equally spaced from a longitudinal vertical median plane through the skate. Pairs of longitudinally spaced aligned vertical slots 14 are provided in the opposed walls 13, and the ends of shafts or pins 15, on which wheels or rollers 16 are mounted between the walls 13, register 10 slidably and rotatably in the slots 14. Curved end walls 17 and 18 extend downward from the front and rear ends, respectively, of the plate 12, integral with the curved ends of the side walls 13, and thus provide together with the latter a housing extending downward from the plate 12 and open only at the bottom. The rollers 16 project through the open bottom of the said housing, indicated at 19. At the forward end of the housing 19, a roller 20 is provided, rotatably supported between the walls 13, and in like fashion a roller 21 is mounted at the rear end of the housing.

In the form of the invention illustrated in Fig. 2, a layer of rubber 22 is secured in any desired manner against the underside of the plate 12 between the walls 13. This layer 22 is provided above the rollers 16 only, and tongues 23 provided at the forward and rearward ends of the layer, which tongues project downward from and integral with the plate 12, confine the rubber layer against forward or rearward movement with respect to the plate.

Each roller shaft 15 is supported in the lower ends of the opposed arms 24 of an inverted U-shaped frame 25, the arms 24 being vertically 35 slidable between the walls 13 of the housing 19. The top member 26 of the inverted U-shaped frame or yoke 25, is in position under and in contact with the bottom of the rubber layer 22. Further, each top member 26 of the yoke 25 is 40 provided, at the front and rear edges thereof, with downturned extensions or flanges 27; each such flange 27 of one yoke is in slidable engagement with the adjacent flange 27 of the neighboring yoke, as shown in Fig. 2, the two outermost flanges 27, of the end yokes, being in slidable engagement with the tongues 23. It is thus apparent that each yoke 25 and hence also its roller 16 is separately and independently vertically moveable, so that when a bump in the floor or road surface is met the roller passing over the bump will independently rise while compressing the rubber 22, thereby very greatly reducing the shock to the skate as a whole.

In the modified cushioning structure shown 55 in Fig. 5, the only difference is that the rubber

cushion is eliminated, and instead a compression spring 27a is mounted between each yoke top 26 and the plate 12; the functioning of the wheels and yokes is thus identical in this modified form.

Figs. 6 and 7 illustrate a further modification or addition consisting in means for accommodating the skate to serve for figure skating.

For this purpose the front wall 17a of the housing 19, which is otherwise identical to the housing 19 of Figs. 1 and 2, has a threaded opening therethrough intermediate its length in which a screw 28 is threaded and from which it projects. A tip or bumper 29 comprising a yoke 30 including the saddle 32 and the opposed arms 31, has a serrated block 33 integral on the saddle 32. Aligned openings 34 are provided in the extremities of the arms 31, and an arcuate tongue 35 extends upward from the saddle 32 and is provided with a longitudinal slot 36. The member 29 is mounted on the housing 19 by registering the ends of the front roller shaft 15a in the openings 34 of the yoke arms 31 with the latter positioned outside the side walls 13, and with the screw 28 passing through the slot 36 of the tongue 35. Thus, the bumper 33 is longitudinally slidably mounted on the front of the front wall 17a and is adapted to be locked thereagainst by the screw 28 at any longitudinal position permitted by the length of the slot 36. It is desirable that the longitudinal position of the bumper 33 be variable to accommodate the skate to the individual figure skater as well as to the kind of steps the skater wishes to indulge in.

Obviously, modifications in form or structure may be made without departing from the spirit or scope of the invention.

I claim:

1. A roller skate comprising a plate adapted to have the sole of the shoe of the user rest thereon, opposed longitudinal side walls extending downward from the underside of the plate equidistant from an imaginary vertical plane through the longitudinal median line of the plate, said side walls having spaced pairs of aligned vertical slots therethrough near the

lower edges thereof, rollers mounted between said side walls, each of said rollers having a shaft extending therethrough, the ends of said shaft passing through one of said pairs of aligned slots thereby mounting said rollers vertically slidably between said side walls, each of said rollers having a yoke including a saddle and depending arms mounted between the roller and said side walls, said yoke arms having holes in the lower ends thereof, said ends of said shaft passing through said holes, and yieldable means mounted between said saddles and said plate, each of said saddles having downwardly extending flanges on the longitudinally opposed transverse edges thereof, each of said flanges except those at the ends of the skate being positioned in vertically slidable engagement with the said flanges of the adjacent saddles, said plate having downwardly extending tongues near the ends of the skate, the outermost of said flanges slidably engaging said tongues.

2. The roller skate set forth in claim 1, said yieldable means comprising a continuous layer of rubber secured to said plate and having a length equal to the sum of the lengths of said saddles and a width equal to the width of said saddles.

3. The roller skate set forth in claim 1, said yieldable means comprising a compression spring mounted between each of said saddles and said plate.

ERNEST KAHLERT.
